UNITED STATES PATENT OFFICE

HAROLD W. CLARK, OF ALLIANCE, OHIO, ASSIGNOR TO THE BUCKEYE JACK MANUFACTURING COMPANY, OF ALLIANCE, OHIO, A CORPORATION OF OHIO

SCREW JACK MECHANISM

Application filed April 10, 1929. Serial No. 353,954.

This invention relates to screw jack mechanism, and more particularly to a mechanism employed with lifting jacks of the double screw type for controlling the rotation of the screws employed.

In the British patent to Hill, No. 62 of 1857, there is illustrated a double screw jack comprising a standard having a rotatable collar mounted thereon and effective for raising and lowering a sleeve therein. A second screw is threaded into the sleeve and rotation of the collar is effective for raising and lowering the screws. It is desirable to elevate the outer screw or sleeve first, and in my pending application Serial No. 322,644, showing a mechanism generally similar to that illustrated herein, there is described and claimed means for effecting this result. The present application constitutes an improvement on the invention of my said prior application.

In the accompanying drawings illustrating the present preferred embodiment of the invention,

Figure 1 is a vertical section taken through the jack and illustrating the lifting screws,

Figure 2 is a horizontal section taken on the line II—II of Figure 1,

Figure 3 is a side elevation, partly broken away, of the lifting screws, and

Figure 4 is a horizontal section taken on the line IV—IV of Figure 1.

The illustrated jack comprises a base 2 having an upstanding portion 3 with an inwardly turned flange 4 on which is mounted a ball bearing 5. A nut 6 lies over the ball bearing 5 and carries a sleeve 7, which is preferably formed from a sheet of metal bent to tubular form. It is fastened to the nut 6 by welds 8. The sleeve 7 has a bearing on the portion 3 of the base at 9 and 10, and at its lower end it carries a bevel gear 11 secured to the sleeve by welding, as indicated at 12. A bevel pinion 13 is journaled in the base at 14 and is held in place by a

split ring 15. The pinion is provided with a socket 16 for the reception of a jack operating handle. It will be noted that when the pinion is in place the nut 6 is held securely against its bearing 5. The assembly and disassembly of the jack is therefore an extremely simple matter, the positioning of the pinion being alone relied on to hold the parts in place.

By reason of this construction it is possible to use a very inexpensive bearing 5. As will be seen from Figure 1, the bearing consists of a U-shaped annular race 17 which contains the bearing balls 18. This bearing may be manufactured at very low expense and the balls simply lie in the race 17 until the jack is assembled. After assembly the jack can be turned to any position without danger of the balls getting out of their race.

The nut 6 is threaded to accommodate a main lifting screw 19, which screw itself is internally threaded to receive a secondary lifting screw 20. The secondary lifting screw 20 is provided with a head 21 to engage the automobile axle or other article which is to be lifted.

The main lifting screw 19 is provided adjacent its bottom with a cross pin 22 adapted to engage ribs 23 on the inside of the base portion 3 during the major portion of the lifting movement of the screw. The engagement of the pin 22 with the ribs 23 prevents rotation of the screw, whereby rotation of the nut 6 causes the screw to be raised or lowered. Near the top of the lifting movement of the main screw 19, the pin 22 is elevated to a position clear of the ribs 23, whereupon the screw 19 is free to rotate with the nut 6; and since the secondary screw 20 is held against rotation by reason of the engagement of the head 21 with the article to be lifted, rotation of the nut 6 causes the screw 20 to be threaded out of the screw 19.

The ribs 23 are terminated short of the bottom of the jack so that the screw 19 may turn

freely in its bottom position. This provision is made because there is no positive mechanism for insuring sequential retraction of the screws 19 and 20, and it may happen that the 5 screw 20 will be partially extended when the screw 19 has reached its bottom position. In such cases it is necessary that the screw 19 be rotatable so as to thread the screw 20 back to its bottom position. As shown in Figure 1, 10 the ribs 23 terminate at 24 and the pin 22 lies therebelow when the screw 19 is retracted.

The feature of the present invention is a ratchet mechanism for controlling the screw 19 when it is in this lowered position. The 15 ratchet proper comprises a sleeve 25 which embraces the bottom portion of the screw 19 and is preferably bent up from sheet metal, as best shown in Figure 4. The bottom end of the screw 19 is of reduced diameter as indicated at 26, so as to limit upward movement of the sleeve, and downward movement is limited by the pin 22 which engages shaped recesses 27 formed in the sleeve 25. The sleeve is further provided on its bottom edge 20 with ratchet teeth 28 adapted to engage up-standing ribs 29 on the bottom portion of the base.

During lowering of the jack, the bevel gear 11 with its connected parts is rotated counter-clockwise, as viewed in Figure 2. If the screw 19 has reached its bottom position while the screw 20 is still extended, it is necessary that the screw 19 rotate counter-clockwise with the bevel gear 11. The ratchet teeth 28 are 30 so inclined as to permit of this rotation and the jack can therefore be actuated until the screw 20 is entirely retracted, without danger of the parts binding.

Now assume that it is desired to elevate the 40 jack. The bevel gear 11 is rotated clockwise and the teeth 28 engage the ribs 29. The screw 19 tends to rotate with the nut 6, and this brings the pin 22 into engagement with inclined faces 30 of the recesses 27, resulting 45 in a cam action which urges the sleeve downwardly and insures that the teeth 28 will continue to engage the ribs 29. The screw 19 being thus effectively locked against rotation, it is raised by the rotation of the nut 6, the 50 ratchet continuing to engage the teeth 29 until the pin 22 has been elevated a sufficient distance to engage the ribs 23.

I have illustrated and described a present preferred embodiment of the invention. It 55 will be understood, however, that it is not limited to the form shown but may be otherwise embodied within the scope of the following claims.

I claim:

60 1. A jack comprising a base, a rotatable nut carried thereby, a lifting screw threaded in the nut and effective for lifting movement on rotation of the nut, means carried by the screw and engageable with the base for limiting rotation of the screw during the major

portion of its travel, a lug on the base and a ratchet carried by the screw cooperating with said lug for limiting rotation of the screw to one direction during another portion of its travel. 70

2. A jack comprising a base, a rotatable nut carried thereby, a lifting screw threaded in the nut and effective for lifting movement on rotation of the nut, means carried by the screw and engageable with the base for limiting rotation of the screw during the major portion of its travel, a lug on the base and a ratchet carried by the screw cooperating with said lug for limiting rotation of the screw to one direction during another portion of its travel, the ratchet comprising a toothed sleeve 75 embracing the screw. 80

3. A jack comprising a base, a rotatable nut carried thereby, a lifting screw threaded in the nut and effective for lifting movement on rotation of the nut, a pin carried by the screw and engageable with the base for limiting rotation of the screw during the major portion of its travel, a lug on the base and a ratchet carried by the screw cooperating with said lug for limiting rotation thereof to one direction during another portion of its travel, the ratchet comprising a toothed sleeve embracing the screw above the pin, the pin extending through the screw for 90 limiting the downward movement of the sleeve relative to the screw. 95

4. A jack comprising a base, a rotatable nut carried thereby, a lifting screw threaded in the nut and effective for lifting movement on rotation of the nut, a pin carried by the screw and engageable with the base for limiting rotation of the screw during the major portion of its travel, a lug on the base and a ratchet carried by the screw cooperating with said lug for limiting rotation thereof to one direction during another portion of its travel, the ratchet comprising a toothed sleeve embracing the screw above the pin, the pin extending through the screw for limiting the movement of the sleeve, the sleeve having a portion shaped to engage the pin and urge the teeth of the ratchet to operative position. 100

5. In a lifting jack, the combination with a hollow post on a base, a screw therein and a nut on the post for actuating the screw, of a pin on the screw and a rib on the post for locking the post against rotation during a portion of its movement, a toothed sleeve 110 loosely mounted on said screw serving as a ratchet, and a lug on said base adapted to engage the sleeve for locking the screw when said pin and rib are ineffective. 115

6. In a lifting jack, the combination with a hollow post on a base, a screw therein and a nut on the post for actuating the screw, of a pin on the screw and a rib on the post for locking the post against rotation during a portion of its movement, a toothed sleeve 120

loosely mounted on said screw serving as a ratchet, and a lug on said base adapted to engage the sleeve for locking the screw when said pin and rib are ineffective, said sleeve 5 having cam surfaces for engaging the pin whereby the sleeve effectively engages the lug until the pin engages the rib.

In testimony whereof I have hereunto set my hand.

10
